UNITED STATES PATENT OFFICE.

GEORGE HOWLETT DAVIS, OF WEST ORANGE, NEW JERSEY.

APRON-FEED FOR PERFORATING-MACHINES.

1,094,537.

Specification of Letters Patent. Patented Apr. 28, 1914.

Application filed October 24, 1912. Serial No. 727,523.

To all whom it may concern:

Be it known that I, GEORGE HOWLETT DAVIS, a citizen of the United States, residing in the town of West Orange, county of Essex, and State of New Jersey, have invented certain new and useful Improvements in Apron-Feeds for Perforating-Machines, of which the following is a specification.

In my prior Patent, No. 659,053, dated Oct. 2, 1900, I have shown and described a form of apron feed for drawing a single sheet or a number of sheets of paper through a music roll perforating machine. It is now and has been the practice for many years to mount the rolls of paper to be perforated upon a rack and draw the separate sheets from such rolls over guides to the point where they pass into the perforating machine. Reliance for drawing the paper through the machine has been entirely placed upon some feeding mechanism such for example as that described in my above named patent. It is quite obvious however that the tension of the several strips of paper as they are drawn from their respective rolls will not be uniform. These various tensions among the strips of paper are due to many causes, as friction in spindles upon which the rolls are mounted; friction of guide rollers; etc. Their effect upon the paper is frequently to throw the edges of the superposed strips out of alinement as they pass along the guides of the perforator up to the punches.

It might be thought that the guides, and rollers located along the edges of the strips would rectify or justify all of the edges; but in practice a particular strip with its edge out of alinement as it enters the machine, will so remain all the way through and as a consequence the perforations of such a strip will be inaccurate, and the completed roll will not track properly in the player instrument for which it was intended. The gist of the difficulty lies in permitting the strains and tensions to take place in the several strips of paper just at the point where they enter the guides of the perforator. Since adopting the mechanism hereinafter described for overcoming these tensions in the paper, no losses from inaccurately alined perforations have occurred; while prior to that time, the losses were heavy and frequently an entire "cutting" had to be thrown out as worthless.

The object, therefore, of my improvement

is to obviate the difficulties above pointed out and to provide mechanism whereby varying strains and tensions in the several strips of paper will be entirely overcome, and the natural phenomena of gravity and agitation allowed to do their work in properly alining the edges of the several strips of paper.

In carrying out my invention I make use of the arrangement of parts as illustrated in the accompanying drawings in which—

Figure 1, is a side elevation of a type of perforating machine, with improved apron feed attachment. Fig. 2, illustrates in side elevation a slightly modified form of driving mechanism for the feed. Fig. 3, is a similar view showing a modified form of apron feed. Fig. 4, is a cross section of the apron feed showing a form of clamping plate similar to that shown in my aforesaid patent. Fig. 5, is a view similar to Fig. 4, but showing a modified form of clamping plates. Figs. 6, 7, and 8 illustrate in detail the upper and lower clamping plates. Fig. 9 illustrates a cross sectional view of the side frame of the apron feed showing the tracks for the anti-friction rollers carried by the clamping plate. Fig. 10 illustrates an enlarged detail view of the ratchet mechanism.

The details of the perforating machine are fully described in my prior patent above referred to, and need not be further described here than to set forth its general features. It consists of the table 1, upon which are mounted the punch setting devices 2, 3, the punch operating mechanism 5, and the forward apron feed 6, all substantially as described in my said prior patent. Power is communicated to the pulley 7, through the belt 8, from any convenient source, and by it the shaft 9, is driven at a high rate of speed. The apron feed 6, serves to draw the several superposed strips of paper 10, through the machine and beneath the punches, all as described in said prior patent. If, now, the paper is drawn directly from the rolls 11, as they are mounted upon the rack 12, the strains and tensions will be such as to disturb the alinement of the edges of the superposed strips, and cause some to crowd over upon one side and others upon the opposite side of the guideway 13 leading to the punches. To avoid this, I provide a second apron feed 14, alike in all essential respects to the apron feed 6, but so located with respect to the end of the perforator table 1, as

to permit a portion of the superposed strips of paper to form a loop 15, hanging down from the apron feed 14. This apron feed is driven by means of an eccentric 16 upon the shaft 9, with the connecting rod 17 leading therefrom to the ratchet drive mechanism 18.

The paper rack 12, is shown as mounted upon an elevated platform 19, with the strips of paper leading from the several rolls 11 to the guide rollers 21, thence downward through the apron feed 14, which latter is firmly secured to the edge of the platform 19. At the end of the table 1, I provide an inclined frame 22, in which are supported a plurality of guide rollers 23, through which the paper is threaded, thence leading it through the machine to the apron feed 6. The speeds of the two apron feeds 6 and 14, are exactly the same, so that after forming the loop 15, it is constantly maintained.

The details of the apron feed as hitherto described are substantially the same as those illustrated in my prior patent. As hitherto described, the apron feed 6 and the apron feed 16 are substantially the same, and a description of one will suffice for the other. Two supporting plates 26 are secured to the end of the table 1, and project horizontally from said table. They are located at a distance sufficiently far apart to receive the multi-ply strips of paper as they pass through the perforating mechanism 5. The supporting plates 26 are substantially alike except one is a "right" and the other is a "left" and they are each provided with offset arms 27, 28, 29, and 30 which carry the sprocket shafts 31, 32, 33, and 34. Upon each of the sprocket shafts is mounted a pair of sprocket wheels as 35, which are located closely adjacent to the arms 27, 28, etc. Around these eight sprocket wheels are carried the four chains 36, 37, 38, and 39, and they are provided at intervals throughout their length with cross plates 40 and 41. These cross plates are connected to specially formed links 42, as shown in Figs. 6 and 7, in any convenient manner. The cross plates 41 upon the upper chains are provided with the pressure plates 43, which are secured to the plates 41 by means of the headed bolt 44, which latter is surrounded by the spring 45 to cause the plate 43 to be spring pressed away from the plate 41. I also provide the guide plate 46 upon the plate 41 to guide the plate 43 in its reciprocations toward and away from the plate 41. The plates 43 and 40 are so arranged upon the chains 36, and 37 that as the sets of chains travel together, said plates will register, and the plate 43, being a spring pressed plate, will be clamped against the corresponding plate 40, by means of the spring 45 or clamp the material as for example, multi-ply strips of paper 10, as clearly illustrated in Fig. 8.

If desired, I may substitute for the springs 45 between the clamping plate 43 and the cross plate 41, the heavy strip of rubber 48, as shown in Fig. 5.

Upon the inner sides of the frames 26, are the tracks 26' between which the sprocket chains are drawn, and which serve to draw the plates 40 and 41 together, and cause the pressure plates 43 to bear with considerable pressure upon the plates 40. Rollers 40' and 41' are provided upon the ends of the plates 40 and 41 to relieve their friction upon the tracks 26'.

As a means for driving the sprocket chains, and as a consequence feeding the multi-ply strips of paper through the perforating machine, I may employ substantially the same mechanism as described in my aforesaid prior patent, or I may use the mechanism illustrated in the drawings as follows: Projecting upwardly from each of the side plates 26 is a supporting arm 49, which latter carries upon the stub shaft a gear wheel 50 and a ratchet wheel 51 rigidly connected together, the gear wheel meshing with a larger gear wheel 52, rigidly mounted upon the end of the shaft 33. Upon the upper end of the arm 49 is pivoted the flat plate 53, which latter carries a pawl 54 for engagement with the teeth of the ratchet wheel 51. The spring 55 bears upon the back of the pawl 54, so as to maintain its engagement with the teeth of the ratchet wheel 51. The plate 53 as hitherto described, is oscillated by the connecting rod 56 which in turn is connected to an eccentric upon the shaft 9 of the punch operating mechanism.

The structure of the apron feed 14 as hitherto set forth is essentially the same as the apron feed 6, just described. Minor details of differences however, will now be described. The gear wheel 50 and ratchet wheel 51 with its pawl mechanism 53, 54, and 55 instead of being mounted upon the projecting arm are mounted directly upon the side frame 26 of the apron feed. The connecting rod 17 leads from the eccentric mounted upon the shaft 9 directly to the plate 53 to oscillate the same and cause a step by step rotation of the ratchet wheel 51 and through it and the gear connections a step by step advance of the chains of the apron feed, as will be readily understood. In this case as hitherto described, the entire apron feed is supported from the elevated platform 19 which also carries the individual rolls 11 from which the strips of paper are drawn. Any convenient method of securing the apron feed 14 to this elevated platform may be used so long as it is firmly braced. I have shown a depending plate 60 bolted to the edge of the elevated platform, as shown with a cross plate 61 rigidly secured to the side frames 26 for 130

supporting said side frames from the plate 60. I also show a brace 62 for connecting the side frames 26 with one of the beams 63 which supports the elevated platform.

5 As shown, the multi-ply strips of paper are drawn from the rolls 11 down through the apron feed 14 from which it is suspended in the loop 15 before it passes through the guide rollers 23. As above described, the 10 shake or vibration of the perforating machine serves to shake the loosely superposed strips into exact alinement at their edges, so that when it passes beneath the perforating punches, this exact alinement is preserved and every sheet is perforated accurately.

In Fig. 2, I have shown a slight modification of the upper apron feed. Instead of connecting the pawl and ratchet mechanism 20 directly to the side frame of the apron feed 14, I mount the same upon the end of the table 1 and provide a sprocket wheel 70 and chain connection 71 with a corresponding sprocket wheel 72 upon one of the sprocket 25 shafts 33 of the apron feed 14. I find that this form of structure answers very well and relieves the apron feed 14 very materially of the vibrations due to the reciprocation of the connecting rod 57. The vibration of the 30 perforating machine itself, however, is communicated to the loop 15 and the result of alining the edges of the strips of paper is identically the same.

In Fig. 3, I have shown a still further 35 slight modification of the upper apron feed. In this case, I dispense with the sprocket chains and their cross plates and substitute therefor a pair of feed rollers 65 and 66, which are supported upon a frame 67, which 40 latter is mounted upon the edge of the elevated platform 19. These rollers are driven by the same kind of ratchet mechanism as hitherto described. In order to insure proper pressure between the rollers as they 45 draw the strips of paper between them, I may cover one of the rollers as 65 with bands of rubber as 68. The paper in this case is drawn from the rolls in the rack upon the elevated platform in substantially the same 50 manner as hitherto described, and is led down through the loop 15 where it is shaken or agitated by the vibrations of the perforating machine into proper alinement.

The various forms of apron feed all 55 template the drawing of the strips of paper into the slack loop 15 prior to their passage into the perforating machine proper, and while I have shown in the drawings several of the forms which my improvement may 60 take, I do not wish to be considered as confining my invention to the forms illustrated and described, for it consists primarily of providing mechanism for drawing the several strips of paper from their individual 65 rolls and permitting said strips of paper to

hang loosely in a loop or festoon whence it may be drawn through the perforating machine by the forward apron feed 6 with the edges of the strips of paper in accurate alinement.

70

I claim:

1. In a system for perforating multi-ply sheets of paper, the combination with perforating mechanism, of a rack for containing the paper in individual rolls, intermittent feeding mechanism for drawing the sheets of paper from said rolls to permit the same to form a suspended loop before passing into said perforating mechanism, intermittent apron feeding mechanism in advance of said perforating mechanism for drawing said paper therethrough, and means for actuating both of said feeding mechanisms in unison whereby said suspended loop is maintained.

75

2. In a system for perforating multi-ply strips of paper, the combination with suitable perforating mechanism, of means for causing several superposed strips of paper to form and maintain a suspended loop before passing into said perforating mechanism, and means for drawing said superposed strips through said perforating mechanism.

80

3. In a system for perforating multi-ply strips of paper, the combination with suitable perforating mechanism, of mechanism for intermittently feeding a plurality of superposed strips of paper to said perforating mechanism, and for forming and maintaining said strips in a slack festoon or loop before passing into said perforating mechanism.

85

4. In a perforating system, the combination with suitable perforating mechanism, a rack for supporting the strips of paper in separate rolls, intermittent feeding mechanism for drawing said strips of paper from said rolls, and for forming and maintaining the superposed strips in a hanging festoon or loop before they are drawn into said perforating mechanism, and intermittent feeding mechanism for drawing said strips of paper from said loop through said perforating mechanism.

90

5. In a perforating system, the combination with suitable perforating mechanism, of a rack elevated above said perforating mechanism for supporting a plurality of strips of paper in individual rolls, intermittent feeding mechanism for drawing said strips of paper from said rolls downwardly to form a suspended loop and a second feeding mechanism for drawing said strips of paper through said perforating mechanism from said loop.

95

6. In a perforating system, the combination with suitable perforating mechanism, of a rack elevated above and independent of said perforating mechanism for supporting

100

110

115

120

125

- a plurality of strips of paper in individual rolls, intermittent feeding mechanism for drawing said strips of paper from said rolls downwardly to form a suspended loop, a second intermittent feeding mechanism for drawing said strips of paper through said perforating mechanism from said loop and means for actuating said feeding mechanism in unison to maintain said loop.
- 10 7. In a perforating system, the combination with suitable perforating mechanism of means for drawing a plurality of superposed strips of paper through said perforating mechanism, and means for forming and
- 15 maintaining said superposed strips in a slack festoon or loop in advance of their passage through said perforating mechanism.
8. In a system for perforating multi-ply sheets of paper, the combination with perforating mechanism, of a rack for containing the paper in individual rolls, step by step feeding mechanism for drawing the sheets of paper from said rolls to permit the same to form a suspended loop before passing into
- 20

said perforating mechanism, step by step 25 apron feeding mechanism in advance of said perforating mechanism for drawing said paper therethrough, and means for actuating both of said feeding mechanisms in unison whereby said suspended loop is maintained.

9. In a perforating system, the combination with suitable perforating mechanism, a rack for supporting the strips of paper in separate rolls, step by step feeding mechanism for drawing said strips of paper from said rolls, and for forming the superposed strips into a hanging festoon or loop before they are drawn into said perforating mechanism, and step by step feeding mechanism 35 for drawing said strips of paper from said loop through said perforating mechanism.

In testimony whereof I have hereunto set my hand this 23d day of Oct. 1912.

GEORGE HOWLETT DAVIS.
